UNITED STATES PATENT OFFICE.

CHARLES G. RAUCH, OF TULSA, OKLAHOMA.

BIT RACK FOR VEHICLES.

Application filed May 5, 1927. Serial No. 189,107.

The invention relates to devices for carrying drill bits and the like, and has for its object the provision of a device including a tray to be secured within the motor vehicle, such for instance as in the boot of the coupé type of automobile, and provided with supporting means for holding the bits in position for transportation.

A further object of the invention is the provision of a bit rack for the purpose stated including an adjustable supporting member that is adapted to be raised and extended outside of the boot of the coupé to hold the bits or other devices to be transported in position, the device being designed to obviate the necessity of cutting the walls of the boot for accommodating the bit, and the adjustable rack is adapted to be closed within the tray when not in use so that the boot cover may be closed to conceal the rack.

The invention will be described in detail hereinafter and will be found illustrated in the accompanying drawings in which

Figure 1 is a side view of a coupé type of automobile showing the rack in position therein and in extended position for transporting bits or other tools,

Figure 2 is a plan view, the adjustable member being in a closed position to permit closing of the cover of the boot,

Figure 3 is a rear view showing the adjustable member in extended position,

Figure 4 is a plan view of the rack member removed from the coupé boot, the adjustable member being in extended position, and

Figures 5 and 6 are transverse sectional views on lines 5—5 and 6—6 respectively of Figure 4.

In the drawings similar reference characters will be used to designate corresponding parts throughout the several views.

The improved bit rack is adapted to be used in connection with a coupé type of automobile and is so designed, as heretofore stated, that when the device is to be used for conveying bits or other tools, an extensible rack is moved in position to support the tools above the rear wall of the coupé boot, and when in a closed position the device will not interfere with the closing of the boot top. In the drawings a coupé boot is indicated at A, and shows the improved bit rack in position therein and including a tray 1 having side walls 2 and an end wall 3. A transverse rest member 4 connects the

side walls 2 and is provided with recesses 5 forming the rest for the bits or other tools being transported.

An adjustable member is also provided and has side arms 6 having longitudinal slots 7 therein and 8 are thumb screws engaging in the slots 7 and threadedly engaging plates 9 secured to the side walls 2, washers 10 being carried by said thumb screws and engaging the side arms 6 to clamp the arms in adjusted positions. A cross piece 11 connects the rear ends of the arms 6 and is provided with depressions 12 to form rests for the drill bits or other tools, and another cross piece 13 is secured to the arms 6 at a distance from their ends and provided with depressions 14 also forming rests for the drill bits or other tools.

The rear wall 3 is lower than the side walls 2, and angle members 15 are secured to the side walls and the rear wall to strengthen the joint, and also extends above the upper edges of the rear wall to provide a support for the cross piece 13 when the adjustable rack is arranged in extended position as shown in Figures 1 and 4, 16 also indicating a plate extending above the upper edge of the rear wall to add to the support of the cross piece 13 when in said extended position. Roller 17 is provided having one of its ends fitted in a circular opening 18 in one side arm 6 and having its other end engaging in a notch 19 in the other side arm 6, said roller being provided to permit of rolling the drill bit or other tool onto the rack.

The cross piece 13 is provided with a leg member 20 having an open slot 21 in its lower end to receive a thumb screw 22 threaded into the rear wall, said thumb screw having a washer 23 to engage the leg member 20 to clamp it in engagement with the rear wall. Each of the side arms 6 are also provided with legs 24 having open slots 25 in their lower ends to engage over thumb screws 26 on which are washers 27 to engage said legs to clamp them in engagement with the side walls, said legs and the connected thumb screws and washers operating to maintain the rack in fixed position relatively to the tray when the rack is in extended position, it being understood also that the thumb screws 8 with the washers 10 thereon also assist in so holding the rack. When the rack is closed within the tray the side arms 6 rest on the thumb screws 26,

and the thumb screws 8 serve to clamp the adjustable rack to hold it in closed position.

As heretofore stated the device may be used in connection with the boot of an automobile coupé and is so constructed as to obviate the necessity of cutting the walls of the boot to accommodate the device for carrying drill bits or other tools and furthermore that the tools will be held so that they will not mar the walls of the boot, and when the device is not in use for carrying drill bits or other tools the adjustable rack may be closed within the tray and the boot so that the boot cover may be closed. It will be furthermore understood that the tray may be secured within the boot by any suitable means, such as screws or other driven fastenings, suggested at 28.

What is claimed is:—

- 20 1. A drill bit rack, comprising a tray adapted to be secured in a vehicle, a rest member fixedly secured in said tray, a rest member adjustably arranged in said tray and adapted to seat on a wall of the tray in one of its positions to provide an inclined support, said rest members having recesses to seat drill bits, and means to secure the last mentioned rest member in adjusted positions.
- 25 2. A drill bit rack, comprising a tray adapted to be secured in a vehicle, a rest member fixedly secured in the tray, another rest member adjustably arranged in the tray, means to secure the last mentioned rest member in adjusted positions, and a roller journaled on the last mentioned rest member.
- 30 3. A drill bit rack, comprising a tray adapted to be secured in a vehicle, a rest member fixedly secured in said tray, an adjustable member including slotted arms slidably mounted on the side walls of said tray, threaded members engaging said side walls and in the slots of said arms, and cross pieces connecting said arms and providing
- 35
- 40

other rest members, one of the last mentioned rest members being adapted to seat on the rear wall of the tray in one position of the adjustable member.

4. A drill bit rack, comprising a tray adapted to be secured in a vehicle, a rest member fixedly secured in said tray and having recesses to seat drill bits, an adjustable member including slotted arms slidably mounted on the side walls of said tray, threaded members engaging said side walls and in the slots of said arms, cross pieces connecting said arms and having recesses therein to seat drill bits, one of said cross pieces being adapted to seat on the rear wall of the tray in one position of the rest member, a leg on the last mentioned cross piece and having an open slot in its lower end, and a threaded member engaging the rear wall of the tray and adapted to engage in said open slot to clamp the leg to the rear wall of the tray.

5. A drill bit rack, comprising a tray adapted to be secured in a vehicle, a rest member fixedly secured in said tray and having recesses to seat drill bits, an adjustable member including slotted arms slidably mounted on the side walls of said tray, threaded members engaging said side walls and in the slots of said arms, cross pieces connecting said arms and having recesses therein to seat drill bits, one of said cross pieces being adapted to seat on the rear wall of the tray in one position of the rest member, a leg on the last mentioned cross piece, a leg on each of said arms, said legs having open slots in their lower ends, and threaded members engaging the side and rear walls of the tray and adapted to engage in said open slots to clamp the legs to the walls of the tray.

In testimony whereof I affix my signature.

CHARLES G. RAUCH.
